UNITED STATES PATENT OFFICE.

EDWARD D. BOOZ, OF BALTIMORE, MARYLAND.

SAFETY GAS-COCK.

SPECIFICATION forming part of Letters Patent No. 771,040, dated September 27, 1904.

Application filed April 18, 1904. Serial No. 203,589. (No model.)

To all whom it may concern:

Be it known that I, EDWARD D. BOOZ, a citizen of the United States, residing at Baltimore, State of Maryland, have invented certain new and useful Improvements in Safety Gas-Cocks, of which the following is a specification.

My invention relates to improvements in safety gas-cocks, and has for its object to provide a device of an improved construction to automatically lock the plug-valve when the latter is turned to the cut-off position and prevent the accidental turning of the valve again as the hand is removed from the key.

The invention is illustrated in the accompanying drawings, Figure 1 illustrating a side elevation of the device as the same appears when in the cut-off position; Fig. 2, a vertical longitudinal section through the cock and plug-valve, the latter being shown in the cut-off position. Fig. 3 illustrates a side elevation of the cock and plug-valve as the same appears when in the open position, the lower portion of the valve being sectioned. Fig. 4 shows a vertical section on the line 4-4 of Fig. 5. Fig. 5 is a horizontal section on the line 5-5 of Fig. 3, and Fig. 6 illustrates a bottom plan view of the cap-plug.

In the drawings, *a* designates the socket member of a gas-bracket which is to be attached to a supply-pipe in the usual manner. This socket member is provided with the usual passage-way *a'* and conical valve-seat *a''* and receives the conical plug-valve *b*, which is secured in the usual or any preferred manner. The socket member is also provided adjacent the valve-seat with the usual segment-flange or stop *a''*. The plug-valve is provided with a horizontal port *b'*, which when the plug is turned may be made to register with the passage-way *a'* in the socket member, so that gas may flow through the latter. Beneath the port *b'* the plug is provided with an interior chamber *b''*, the wall of which at its lower end is screw-threaded, and said plug is also provided with an annular exterior horizontal flange *b''*. A cap-plug *c* screws into the lower end of said plug-valve *b* and closes the lower end of the chamber *b''*, and said cap-plug is provided with an exterior vertical groove *c'* and a bottom recess *c''*. Two vertical pin-

holes *c''* are also provided on the interior of the cap-plug for a purpose to be presently described.

An operating-key *d* has a stem *d'*, which extends through the cap-plug *c*, and also has a circular head *d''*, which fits into the recess *c''* of the cap-plug, and two vertically-extending pins or fins *d''*, which take in the holes *c''* of the cap-plug. A pin *e* extends horizontally through the stem *d'* and projects slightly at 6c either side thereof, and a washer *e'* has position on the stem beneath the pin *e*. A spiral spring *f* surrounds said stem and has its upper end contacting with the washer and its lower end seated on the cap-plug *c*. This 65 spring *f* serves to keep the stem *d'* normally pressed up.

A pin *g* is secured in the key *d* and extends vertically in a direction parallel with the stem *d'*. This pin *g* passes through the vertical groove *c'* in the cap-plug and also through the horizontal flange *b''* on the exterior of the plug-valve, and the upper end of said pin terminates above the said flange. It will thus be seen that the horizontal flange *b''* serves as a 75 guide-bearing for the pin *g*. When the stem is pressed up, as in Fig. 1, the upper end of the pin *g* will engage one of the ends of the segment-flange *a''* on the socket member. A stationary pin *g'* is secured in the horizontal 80 flange *b''* and extends vertically toward the socket member *a*. This pin *g'* has position at the side of the valve-plug and diametrically opposite the vertically-movable pin *g*, as clearly seen in the drawings. When the valve 85 is in the cut-off position, the movable pin *g* has position in front of one end of the segment-flange stop *a''*, while the stationary pin *g'* on the flange *b''* has position at the opposite end of said stop. This is a useful construction in that it insures that the fixed pin will 90 always contact with the stop *a''* when the valve-plug is given a half-turn, and the movable pin will automatically lock the valve to prevent accidental turning.

The operation of the device is simple and as follows: When the valve-plug *b* and stem *d'* are in the position shown in Figs. 1 and 2, the ports are in the cut-off position and are locked in that position by the pins *g* and *g'*, 100

contacting with opposite ends of the segment flange or stop a^3 . The pins or fins d^3 on the circular head d^2 permit vertical movement of the key independently of the plug-valve, but prevent the key from being rotated independently of the plug-valve. In order to turn the valve so that the pocket b' will register with the passage-way a' of the socket member, the stem must be pulled down vertically through the valve-plug. This downward movement of the stem causes the pin g to move downwardly through the horizontal flange b^3 and the vertical groove c' in the cap-plug and takes a position below the segment-flange stop a^3 . While the pin g is in this lowered position the stem and plug-valve may be turned together in a horizontal plane, and the end of the said pin g will pass beneath the said segment-flange stop and hold the stem in the lowered position while the ports are in register.

Having thus fully described my invention, what I claim as new, and desire to secure by Letters Patent, is—

1. In a gas-cock the combination of a socket member having a passage-way and a segment stop-flange; a plug-valve in said socket member; a pin carried at one side of said plug-valve and arranged to contact with said stop-flange when the valve is in the cut-off position, and a pin extending vertically at the opposite side of said plug-valve and movable in a lengthwise direction beneath said socket member.

2. In a gas-cock the combination of a socket member having a passage-way and a segment stop-flange; a plug-valve in said socket member; a pin carried by said plug-valve and having a fixed position with respect to said valve; a key movable in a horizontal plane with said plug-valve but movable in a vertical plane independently of said valve, and a pin extending vertically from said key and in a direction parallel with the plug-valve and terminating beneath the socket member, said pin arranged to be moved in a lengthwise direction when the key is moved vertically.

3. In a gas-cock the combination of a socket member having a passage-way and a segment stop-flange; a plug-valve in said socket member and having an annular exterior flange; a pin rigidly secured in the flange of said plug-valve and extending vertically therefrom; a removable cap-plug at the lower end of said plug-valve and having a bottom recess; an operating-key having a head which fits into the recess of said cap-plug, said key and head arranged to be moved vertically with respect to said valve-plug, and a pin extending vertically from said key and passing through the annular flange of the valve-plug and terminating beneath the socket member.

In testimony whereof I affix my signature in presence of two witnesses.

EDWARD D. BOOZ.
